(57) **CLAIM**

The ornamental design for a stylized window insert set for a garage door, as shown and described.

DESCRIPTION

FIG. 1 is an enlarged front, perspective view of one window insert shown in FIG. 4 of the window insert of the invention; FIG. 2 is an enlarged right side view of one window insert shown in FIG. 4 of the window insert of FIG. 1, the left side view being the reverse image thereof;

FIG. 3 is an enlarged bottom view of one window insert shown in FIG. 4 of the window insert of FIG. 1, the top view being the reverse image thereof; and,

FIG. 4 is a perspective view of the window inserts of the invention in place on a garage door, the garage being shown in phantom lines and not forming a part of the invention.
